UNITED STATES PATENT OFFICE.

JOHN BETZ, JACOB WAMPACH, AND HENRY WAMPACH, OF JORDAN,
MINNESOTA.

WIRE-TWISTING IMPLEMENT.

No. 828,015.

Specification of Letters Patent.

Patented Aug. 7, 1906.

Application filed November 21, 1905. Serial No. 288,421.

To all whom it may concern:

Be it known that we, JOHN BETZ, JACOB WAMPACH, and HENRY WAMPACH, citizens of the United States, residing at Jordan, in the county of Scott and State of Minnesota, have 5 invented a new and useful Wire-Twisting Implement, of which the following is a specification.

This invention relates more particularly to 10 means for attaching stay-wires to the line-wires of a fence, but is not necessarily limited to this use.

One of the principal objects is to provide 15 an implement that may be readily applied to the line-wires and will properly hold the said wires in position until the tie has been made, said implement being made up of elements and combinations of elements that are exceedingly simple, will effectively perform 20 their respective functions, and are not liable to become deranged, but, on the other hand, will withstand the hard wear and rough usage necessarily incident to the employment of a device of this character.

25 An embodiment of the invention that is at present considered the preferable one is illustrated in the accompanying drawings, where-

30 Figure 1 is a perspective view of the implement applied to a fence. Fig. 2 is a side elevation of said implement. Fig. 3 is a view in elevation of the opposite side, showing the wires in position to be tied. Fig. 4 is a similar view after the tie has been made. Fig. 5 35 is a longitudinal sectional view through the implement. Fig. 6 is an end elevation of the same. Fig. 7 is a detail perspective view of the handle-crank and dog carried thereby. Fig. 8 is a detail perspective view of a portion 40 of the supporting-arm. Fig. 9 is a detail perspective view of the wire-holding device.

Similar reference-numerals designate corresponding parts in all the figures of the drawings.

45 In the embodiment illustrated a main support is employed that is in the form of an arm 10, one end of which constitutes a handle 11, the other end being enlarged into a head 12, that is provided with a journal-bearing 13 and a slot 14, that opens through the outer end of the head into said bearing. Journaled in the bearing 13 is a rotatable twisting device, comprising a body 15, having a slot

16, that is movable into and out of alinement with the slot 14. An annular flange portion 55 17, formed upon one end of the body and engaging one side of the supporting-head, serves to prevent longitudinal movement of the twister in one direction, while its movement in an opposite direction is prevented by 60 a handle-crank 18, journaled upon the opposite end of the body and on the opposite side of the arm, this handle-crank being retained by a holding-ring 19, fastened to the adjacent 65 end of the twister.

The handle-crank 18, as already stated, is 70 rotatably mounted on the twister, but is normally held against such rotation by means of a reciprocating dog 20, slidably mounted in the crank longitudinally thereof, the inner 75 end of the dog being arranged to engage in any of a plurality of sockets 21, formed in the body. The dog is urged into the sockets by means of a coiled spring 22, one end of which bears against a stop-pin 23, carried by the 80 dog, the other end bearing against the end of the recess 24, that receives the spring. The front end of the crank 18 is provided with a laterally outstanding offset handle-grip 24^a, and the outer end of the dog is provided with 85 an offset terminal constituting a finger-piece 25, disposed in substantially parallel relation to the handle-grip 24^a and movable toward and from the same.

Projecting from the end of the twister-body having the flange portion 17 is a wire engaging and twisting projection 26, that is preferably located in rear of the slot 16 and which is screw-threaded, and therefore adjustable in said body. On opposite sides of the 90 end of the twister carrying the projection 26 are spaced outstanding lugs 27, carried by the supporting-arm head 12. A wire-holding device cooperates with these lugs and comprises a swinging arm 28, one end of 95 which has a pivotal engagement with the supporting-arm 11 by having an offset longitudinally-disposed nib 29, that engages beneath a web 30, formed in the arm. The other end of this arm 28 is in the form of a yoke, the 100 horns 31 of which are located on opposite sides of the twister and move toward and from the head 12. A leaf-spring 32, secured to the inner side of the arm 28 and bearing against the arm 10, serves to yieldingly urge 105 the yoke away from the head. It is, how-

ever, arranged to be clamped against said head by a cam 33, journaled on a post 34, carried by the arm 10 and extending through the arm 28.

5 In using the implement the slots 14 and 16 of the supporting-head and twister are brought into alinement and the stay-wire is placed in the guideways between the lugs 27 and is clamped by the yoke 31. The implement is
 10 then applied to the line-wire, which is introduced through the alined slots 14 and 16 into the twister. This relation of parts is illustrated in Fig. 3. The twister is then rotated by means of the handle-crank, which may be
 15 turned completely around or which may be given a ratchet movement. This latter movement can be readily secured, for one of the fingers of the hand that grasps the grip 24^a can be employed to operate the dog 20,
 20 the finger-piece 25 being in convenient relation for this purpose. As soon as the desired twist (illustrated in Fig. 4) has been made the holding-yoke 31 is released, a slight retrograde movement is given the handle in order
 25 to detach the projection 26 from the loop formed in the stay-wire, whereupon the implement can be removed and applied at the next place at which a tie is to be made. It will be apparent that by this simple structure stay-wires can be readily applied to line-wires, or, for that matter, any cross-wires can be effectively tied together with ease and expedition.

Having thus described our invention, what
 30 we claim as new, and desire to secure by Letters Patent, is—

1. In a twisting implement, the combination with a support, of a twister journaled in the support and freely rotatable in either direction, an actuating-crank rotatably mounted directly on the twister and located at one side of the support, said crank having an offset handle-grip, and a dog for normally holding the twister and crank against relative movement and permitting their relative adjustment.

2. In a twisting implement, the combination with a support, of a twister journaled in the support and having a retaining-flange portion at one end and at one side of said support, and an actuating-crank carried by the other end portion of the twister and located on the opposite side of the support to the flange portion, forming with said flange portion means for retaining the twister on the support.

3. In a twisting implement, the combination with a support, of a twister journaled in the support, an actuating-crank journaled on the twister and having a lateral offset handle-grip, and a dog movably mounted on the crank and engaging the twister to hold the same and the crank against relative rotation, said dog having an offset finger-piece dis-

posed adjacent and in substantially parallel 65 relation to the handle-grip.

4. In a twisting implement, the combination with a support, of a twister journaled in the support and having sockets, an actuating-crank journaled on the twister and having a handle-grip, and a reciprocatory dog slidably mounted on the crank and engaging in the sockets of the twister, said dog having an actuating finger-piece disposed adjacent in substantially parallel relation to the handle- 75 grip.

5. In a twisting implement, the combination with a supporting-arm, of a twister journaled in the arm, said twister having sockets, an actuating-crank journaled on the twister 80 and having a lateral offset handle-grip, and a reciprocatory dog slidably journaled on the handle-grip and movable into and out of the sockets of the twister, said dog having an offset finger-piece disposed in substantially parallel 85 relation to and movable toward and from the handle-grip.

6. In a twisting implement, the combination with a supporting-arm having a journal-bearing in one end and a slot communicating therewith, of a twister-body journaled in the bearing and having a slot movable into and out of alinement with the slot of the supporting-arm, a flange carried by one end of the twister-body and located on one side of the arm, a handle-crank journaled on the other end of the body and located on the other side of the arm, said body having sockets, and a dog slidably mounted on the crank and movable into the sockets of the body. 90 95

7. In a twisting implement, the combination with a support, of a twister journaled thereupon, means for rotating the twister, and a wire-holding device movably mounted on the support for maintaining a wire across 105 the twister.

8. In a twisting implement, the combination with a support, of a twister journaled thereupon, wire-retaining means mounted on the support at one side of the twister, and a wire-holding device movably mounted on the support and coacting with the retaining means to hold a wire therein. 110

9. In a twisting implement, the combination with a support, of a twister journaled thereupon, and a wire-holding device movably mounted on the support and having a yoke portion that extends on opposite sides of the twister and is movable toward and from said support. 115

10. In a twisting implement, the combination with a support, of a twister journaled thereupon, spaced lugs carried by the support and forming a wire-guideway between them, and a wire-holding device movably mounted on the support and coacting with the lugs to hold a wire in the guideway. 125

11. In a twisting implement, the combina-

tion with a support, of a twister journaled thereupon, said support having guides on opposite sides of the twister, and a wire-holding device having a yoke portion movable toward and from the guides.

12. In a twisting implement, the combination with a support, of a twister journaled therein, a swinging holding device mounted on the support, and a cam for urging the holding device toward and from the support.

13. In a twisting implement, the combination with a supporting-arm, of a twister journaled therein, a handle-crank for rotating the twister, wire-guides formed on the supporting-arm on opposite sides of the twister, a swinging wire-holder having a pivotal engagement at one end with the supporting-arm and having a yoke portion at its other end that is movable toward and from the

guides, a post carried by the support, and a cam journaled on the post and bearing against the wire-holder.

14. In a twisting implement, the combination with a supporting-arm, of a twister journaled therein, a handle-crank connected to the twister on one side of the arm, and a wire-holder mounted on the other side of the arm and movable toward and from the same.

In testimony that we claim the foregoing as our own we have hereto affixed our signatures in the presence of two witnesses.
